UNITED STATES PATENT OFFICE

CHARLES E. CHALMERS, OF NEW YORK, N. Y.

MULTIPLE-CHANGE-MAKING MACHINE

Application filed January 16, 1923. Serial No. 613,077.

This invention relates to a multiple change making machine and is an improvement upon the inventions illustrated, described and claimed in my copending application Serial No. 589,755, filed September 22nd, 1922, and also my copending application Serial No. 613,076, filed on even date herewith. And while the invention is illustrated and described herein as being utilized for effecting change on motive vehicles where a fare is charged it is to be understood that it is not limited to any such use as it will be readily manifest to those skilled in the art that it has numerous other uses which are both kindred and non-analogous to that just mentioned.

Like the two applications just referred to, this invention has to do with a construction which will not only receive the exact fare, but return the necessary change whenever the passenger drops a coin therein of a denomination or value higher than the price of such fare. For the purposes of elucidating the principles of my invention the embodiment hereinafter illustrated and described is designed upon a five-cent fare basis; consequently the change returned, if any, is either five cents or a multiple thereof.

One of the more important features of the present invention is the provision of mechanism for receiving one or a multiple of fares from a coin deposited in the machine, suitable provisions being made in connection therewith for registering the number of fares taken from said coin, or more broadly stated for registering the net amount of cash received by the machine.

In my copending applications above referred to, I have illustrated, described and claimed change carriers provided with a plurality of magazines or pockets which are movably supported in the machine. The present invention, specifically speaking, is an improvement thereover, although not limited thereto, in that the magazines or pockets are preferably stationary and in connection therewith provision is made for extracting one or a multiple of coins from the same magazine depending upon the number of fares to be taken from the particular coin de-

posited. For economical reasons provisions are also made in the case of coins of higher denominations deposited of ejecting change coins from a plurality of said magazines or pockets.

So as to avoid jamming of the machine which would result in depositing a plurality of coins in the coin chute prior to the actuation of the machine, mechanism is provided to prevent the machine from being operated until the actuating handle is manipulated, and in conjunction with this feature of the invention mechanism is provided which serves the purpose of enabling the coin to be inspected to determine whether or not it is genuine or spurious.

The specific embodiment of my invention herein illustrated and described is so constructed that it will deliver change for a quarter, half-dollar, or a dollar after deducting one, two, three or four fares therefrom, and after electing the number of fares to be registered, or, rather, accepted, the same will not be registered on the machine after the deposit of the coin, until the operating handle has been actuated. This prevents tampering by unauthorized persons.

Another feature of the invention consists in the provision of mechanism which enables the operator to restore all parts to normal position by means of an error key should, for any reason, the passenger or conductor, as the case may be, select the wrong number of fares to be deducted from any particular coin deposited.

In conjunction with the features of the invention above related, it may be pointed out that the embodiment illustrated, described and claimed herein is provided with a plurality of selecting devices similar to the selecting devices illustrated, described and claimed in my copending application Serial No. 613,076, filed on even date herewith, above referred to. The machine of this application is also adapted to be provided with coin-controlled mechanism employed for issuing a transfer and simultaneously print on said transfer the time the same was issued. However, the transfer-ticket-issuing-and-printing mechanism is not illustrated in detail, as the

same is only incidentally related to the improvements of this application.

In the embodiment of my invention illustrated and described herein the coins utilized for making change comprise only five and twenty-five cent pieces, as that reduces very materially the bulk of the machine as compared with a machine embodying the same principles and which utilizes only one coin for making change. On the other hand the mechanism is reduced to a much simpler form as compared with a machine embodying the same principles and which is equipped to return more than the stated number of change coins. However, it will be apparent that the invention is not limited to the said specific form hereinafter described and illustrated in the accompanying drawings, nor is it to be understood that the invention is to be limited to a form of machine capable of receiving only a five-cent fare. In short the principles are the same irrespective of the number of coins utilized for making change and irrespective of the fare charged.

In actual practice I have found that very seldom does any particular passenger pay for more than five fares at any one time. Therefore the embodiment herein illustrated and described is designed to return change for one or a multiple up to five fares. If a five-cent piece is deposited, of course no change will be returned. If a ten-cent piece is deposited either one fare may be paid therefrom and five cents returned, or two fares may be paid and no change returned. If a twenty-five cent piece is deposited either one, or two, three or four fares may be paid and the appropriate change returned, or five fares may be paid and no change returned. If a fifty cent piece is deposited either one, two, three, four or five fares may be paid and the appropriate change returned. And if a dollar is given to the conductor one, two, three, four or five fares may be paid and the proper change returned by the machine.

Other features, objects and advantages of the machine will more fully hereinafter appear from the detailed description below taken in conjunction with the accompanying drawings, which illustrate the preferred embodiment of my invention:

Fig. 1 is a front elevation, partly in section, of a machine which illustrates the preferred form of my invention;

Fig. 2 is a top plan view with the casing partly broken away to show parts within. Some of the upper mechanism is also broken away to show the mechanism beneath;

Fig. 3 is a vertical transverse section on line 3—3 of Fig. 1, and illustrates suitable means for preventing the entrance of more than one coin at a time to the coin chute;

Fig. 4 is a fragmentary transverse section on line 4—4 of Fig. 2, and shows a portion

of the quarter magazine for a dollar change; and also counter mechanism for nickels;

Fig. 5 is a vertical transverse section on line 5—5 of Figs. 1 and 2, and shows change mechanism for handling a quarter previously deposited in operative position in the coin chute;

Fig. 6 is a fragmentary sectional view taken on line 6—6 of Fig. 7;

Fig. 7 is a vertical transverse section on line 7—7 of Fig. 1, and shows the dime change stack, counter mechanism, and mechanism for handling a dime;

Fig. 8 is a detail sectional view on line 8—8 of Fig. 2, and shows the slide for delivering change for a half dollar after deducting one, two, three or four fares;

Fig. 9 is a detail sectional view on line 9—9 of Fig. 5, and shows ejecting slides for delivering change for a quarter after deducting one, two, three or four fares;

Fig. 10 is a detail fragmentary view taken substantially on the line 10—10 of Fig. 7;

Fig. 11 is a fragmentary rear view of that portion of the machine illustrated in Fig. 10 the casing being partially broken away to show the counting and associated mechanisms;

Fig. 12 illustrates a view of the change-return trays, and the chutes through which the change is discharged from the various magazines to said trays.

Fig. 13 shows the mechanism by which the number of fares collected by the machine are recorded upon the fare collecting counter.

Fig. 14 is a view showing the multiple fare collecting mechanism and the mechanism which registers the number of fares collected on the fare collecting counter.

It may be stated briefly that the specific form of machine illustrated and described herein is provided with six change magazines two of which are employed in the return of change for a dollar, two of which are employed in the return of change for a fifty-cent piece, one of which is employed in returning change for a twenty-five cent piece, and one of which is employed in the return of change for a dime. The chief object or rather the general scheme of employing six magazines is to enable coins of one denomination only to be contained in each. In the construction illustrated and described, assuming that only one fare is to be paid, the change for a dime is a nickel; the change for a quarter is four nickels; the change for a half dollar is a quarter and four nickels; and the change returned for a dollar is three quarters and four nickels. This arrangement is only preferred because it materially simplifies the construction of the machine.

The change for a dollar is obtained by handing the operator the bill which he keeps in his pocket. He then pulls a special dollar change handle which delivers to the passenger

ger the appropriate change after deducting one, two, three, four or five fares, and simultaneously registers the receipt of said fares on a special counter employed in conjunction therewith.

For convenience I will first describe the mechanism employed in properly locating the respective coins deposited in operative position and then will follow in detail a description of the mechanism employed and rendered operative by the coin deposited for returning the appropriate change.

Referring to the drawings in detail, the reference numeral 10 designates a suitable housing which may be made of one or more parts, and which is preferably provided at its top with a pivoted closure 11 (see Figs. 5 and 7) and at its side with a removable closure 12 (see Figs. 1 and 5) the former being employed to afford access to the change mechanism and the latter to provide access to the compartment into which the coins deposited by the passengers are discharged by the machine. The machine is also provided with an attached compartment 13 (see Figs. 1, 2, 3 and 7) to receive and enclose a part of the change return actuating mechanism, a horizontally arranged base plate 14 (see Figs. 2, 5 and 7), the vertical wall members 15 and 16 (see Figs. 2, 3, 5 and 7) cooperating to form a coin chute, and change receiving trays 17, 18, 19 and 20 (see Fig. 12). The horizontally arranged base plate not only serves as a support for certain mechanism of the machine, but also to divide the housing into a compartment "A" which contains, chiefly, the change magazines 21, 22, 23, 24, 25 and 26 (see Fig. 2), and the mechanism for ejecting the coins therefrom, and a compartment "B" which serves, among other things, as a receptacle to receive the coins deposited by the passengers and through which extends the chutes 27, 28, 29, 30, 31 and 32 (see Figs. 2 and 12) connecting respectively the magazines 21, 22, 23, 24, 25 and 26. The chutes 27 and 28 are for discharging change for the fifty-cent pieces into the tray 17, the chute 29 is for discharging change for quarters into the tray 18, the chutes 30 and 31 are for discharging change for a dollar delivered to the operator into the tray 19, and the chute 32 is for the discharge of change for dimes into tray 20.

The guide for directing the coins into the coin chute is diagrammatically but clearly illustrated in Figs. 1 and 3, and is designated by the reference numeral 33. The wall member 16 is cut away (or cast) on the side adjacent to the wall member 15 to provide a space 34, and connecting the guide 33 with said space 34 is a short passageway 35 (see Figs. 1 and 3) for directing the coins from the chute 33 to the selecting means employed for accepting or rejecting the coins. Within the confines of the space 34 are a plurality

of ribs 36, 37 and 38 to provide passages 39, 40, 41 and 42 (see Fig. 1) for receiving respectively, fifty, twenty-five, five and ten cent pieces from the four selecting devices to be presently described.

Supported in an opening in the wall member 16, just below the short passageway 35, is a removable transparent member 43 held in position preferably by means of a rectangular frame 44. This member is flush with both the interior and exterior sides of the wall 16 and enables the motorman to ascertain at a glance whether or not the particular coin deposited by the passenger is genuine or spurious. This transparent member is clearly illustrated in Figs. 1, 3 and 4 from which it will be seen that for the purposes of securing the same in place the edges are beveled to fit the correspondingly beveled opening in the wall 16.

In the form of the invention illustrated, there are four selecting devices generally designated by the reference characters S1, S2, S3 and S4 (see Fig. 1). These four selecting devices are practically the same in principle, construction and mode of operation; in fact, the only difference of one with respect to the other is in the location of the temporary coin-arresting and supporting means. From the drawings, and from what follows, it will be clearly apparent that such arresting means enables a ten-cent piece to fall into and be arrested by the selector S4, a five-cent piece to fall into and be arrested by the selector S3, a twenty-five cent piece to fall into and be arrested by the selector S2, and a fifty-cent piece to fall into and be arrested by the selector S1. It will therefore be evident that a detailed description of one of these selectors is sufficient to enable anyone to understand the construction and mode of operation of the others, hence only the detailed construction and mode of operation of the selector S1 will be described.

The selector S1 comprises a rectangular bar 45 which slides back and forth in the groove 46 located on the outer side of the wall 15, as clearly illustrated in Figs. 1, 2, 3, 5 and 7. This bar 45 is provided with two pivoted members 47 and 48 and the space between the same constitutes, so to speak, a continuation of the short passage 35. The ends of these members are bent inwardly towards each other as indicated at 49 and 50, so as to arrest a fifty-cent piece between them, suitable resilient means 51 and 52 being employed to normally avoid the spread of one in a direction away from the other. These resilient means normally maintain the toes 53 and 54 of these members in engagement with the stops 55 and 56 projecting laterally from the slideable member 45. After the coin is deposited between the members 47 and 48, as clearly illustrated in Fig. 1, the same may be either accepted or rejected by the motorman, or

operator, depending upon whether or not it is genuine or spurious. If it is accepted, the bar 45 is moved inwardly by exerting a push on the knob 57 until the toe 54 engages with the stop 58. A continuation of the movement of the bar 45 after such engagement with the stop 58 will result in throwing the lower end of the lever 48 outwardly relative to the lever 47, thereby releasing the coin and enabling it to drop by gravity into the chute 39. On the other hand, if it is desired to refuse the coin, an outward movement is imparted to the rectangular bar 45 until the toe 53 of the lever 47 engages with the stop 59. A continuation of the movement of the bar 45 after such engagement of the toe 53 with the stop 59 will result in throwing the lower end of the lever 47 outwardly with respect to the lever 48, thereby releasing the coin and enabling it to be discharged by gravity from the space 34 into the tray 60, as clearly illustrated in Figs. 1 and 2.

Suitable mechanism is essential to maintain the members 47 and 48 in proper alignment with the passage 35. To that end, the bar 45 is provided with a lug 61 (see Figs. 2, 5 and 7), extending through a slot 62 (see Figs. 2 and 3) in the wall 15. Located on the interior wall 15 (see Fig. 2) are supports 63 and 64 for rigidly securing the rod 65, and in turn there is fixed to the intermediate portion of this rod, a stop 66. Encircling this rod on one side of the stop 66 is a coil spring 67 which is provided with a member 68 normally impelled by said spring to engage the stop 66. On the other side of the stop 66 is a coil spring 69 tending to impel the member 70 thereon against the other side of the stop 66. The width of the stop 66 is preferably equal to the width of the lug 61, and the spring members 67 and 69, as will be understood from the foregoing, normally maintain the lug 61 in juxtaposition to the stop 66, and when in this position the pivoted members 47 and 48 are in alignment with the passage 35. When the bar 45 is moved inwardly to deposit the fifty-cent pieces into the passageway 39, it compresses the spring 67, which automatically effects the return of the mechanism to normal position as will be understood. When the bar 45 is moved outwardly to reject a slug, the spring 69 is compressed, and thereby effects the automatic return of the parts to normal position after the bar has been released. The bar 45 is provided with a pin or finger 71 projecting through the slot 62, the purpose of which is to engage the lever 72 of a suitable counter 73, thereby registering the number of coins accepted.

In all their essential parts, the selectors S2,

S3 and S4 are identically the same as the selector S1. The only difference between the selectors is in the spacing of the pivoted coin guiding and arresting members. It will therefore be noted that the members 47 and 48 are properly spaced to receive, guide and arrest the fifty-cent pieces, and that the corresponding members on selectors S2, S3 and S4 are properly spaced respectively to receive, guide and arrest twenty-five, five and ten cent pieces. It will also be noted, however, that these members are substantially in vertical alignment as a result of which the members on selectors S1, S2 and S3 also serve as means for guiding the ten-cent pieces to the lower selector S4; that the members on the selectors S1 and S2 serve as guides for the five-cent pieces to the selector S3; and that the members on selector S1 serve as guides for the twenty-five cent pieces to the selector S2.

The selectors S2, S3 and S4 are actuated in the same manner as selector S1 but serve to deposit the twenty-five, five and ten cent pieces respectively in the bottom of the passageways 40, 41 and 42. It will therefore be apparent from the preceding description that the mechanism enables the operator to observe the coin deposited by the passenger, to return the same if it is a slug, and to receive the same in case it is genuine. If the coin is received, it drops to the bottom of one of the passageways 39, 40, 41 or 42, and renders the machine operative to return the change corresponding to the coins deposited and the fares to be taken therefrom. Of course, if a five-cent piece is deposited, no change will be returned.

In describing the change making mechanism, reference will first be made, arbitrarily, to the device for returning change for twenty-five cents. It will be understood from the foregoing that when a twenty-five cent piece is deposited, it will assume the position in passageway 40 clearly indicated in Figs. 1 and 5. Arranged transversely of the machine, is a main operating shaft 74 one end of which is provided with a suitable operating crank 75. A suitable operating handle 76 is provided on the outer end of the crank 75. The shaft 74 and the crank 75 are held in normal position as indicated in Fig. 5 with the crank 75 in engagement with a suitable stop 77. The shaft 74 is also provided with a member 78 shown in Fig. 3 projecting in a direction substantially opposite to the direction of the crank 75 and to this member is connected one end of a suitable spring 79 the opposite end of which is anchored at 80 to one of the walls of the container. The function of this spring 79 is to return the shaft and crank to normal position. The shaft 74 is further provided at its crank end with an arm 81 (see Figs. 2, 5 and 7) projecting upwardly therefrom, which is provided with a

slotted or forked end 82 which engages with the stud 83 projecting laterally from one end of the bar 84. The latter passes through a guide member 85. The other end of the bar 84 is connected to the crosshead 86. The reference characters 87, 88, 89, 90 and 91 (see Figs. 2, 3 and 6) designate parts located at the opposite end of the shaft 74 which correspond to the parts designated by the numerals 81, 82, 83, 84 and 85 respectively. It may be mentioned, however, that the bar 90 is also connected to the other end of the crosshead 86. Consequently there is provided a direct and positive connection between the two ends of the cross head on the one hand and the shaft 74 on the other, thereby effectively eliminating any side draft in the to-and-fro movement of the cross-head and associated mechanism. The crosshead is equipped with a plurality of fingers 92, 93, 94, and 95, located and longitudinally movable in bearings 96, 97, 98 and 99, respectively, said bearings constituting preferably an integral part of the wall 16. The normal position of the crosshead and fingers and associated mechanism is clearly illustrated in Figs. 2, 3, 4, 5 and 7. When the crank arm 75 is moved in the direction of the arrow "a", on Fig. 5, the crosshead and fingers will be moved inwardly to operate mechanism to return change.

The wall 15 is provided with a plurality of perforations 100, 101, 102 and 103 through which the deposited half-dollars, quarters, nickels and dimes, respectively, are adapted, upon the actuation of the coin ejecting mechanism, to pass from their operative positions to the lower coin-receiving compartment B of the machine. The perforations 100, 101, 102 and 103 are normally occupied by the heads 104, 105 and 106 of the respective ejectors 107, 108 and 109. These heads are in turn provided respectively with perforations 110, 111 and 112 to receive the respective fingers 92, 93 and 95, upon the movement of the crosshead 86 by the operation of the crank 75, provided there is no coin or coins in the bottom of the passageways 39, 40 and 42, if, however, there is a coin in the bottom of one of these passageways, the projection of the finger through the corresponding perforation will thereby be prevented, and the particular coin ejecting mechanism actuated through the intermediary of the coin deposited. There is no ejector corresponding to the nickel since no change is required (see Fig. 4). Hence the nickel deposited in the bottom of the passageway 41 will, upon the actuation of the crosshead 80, be fed through the perforation 102 by the finger 94 and thence to the compartment B via perforation 113 in the division wall 14. As illustrated in Fig. 5 the twenty-five cent piece is properly located in the bottom of the passageway 40, which means that the machine is in operative posi-

tion to receive the twenty-five cent piece and to return the proper change therefor. The machine, as previously stated, is so constructed as to return one, two, three or four five-cent pieces, when a twenty-five cent piece is so deposited.

Reference has been previously made to the feature of preventing a coin from entering the machine, after it has been deposited in chute 33, until the operating handle is actuated. This comprises a slideable member 114 (see Fig. 3) held in position by a suitable keeper 115. Mounted upon the member 114 is a cylindrical device 116 equipped with a spring pressed bolt 117 normally located in the path of the upper end of the operating rod 118. The bolt in turn is equipped with a laterally projecting stud which engages with the camming surface of the cam 119. It will therefore be manifest that when the operating shaft 74 is actuated the rod will be moved in the direction of the arrow "b" carrying with it the bolt 117, cylindrical device 116, and slideable member 114. As the member 114 and cylindrical device 116 are moved to the right the stud on the bolt 117 rides up the surface of cam 119 and imparts a vertical movement to the said bolt 117, and withdraws the same from the path of movement of the upper end of operating rod 118. As soon as released from the rod 118, the bolt 117, device 116 and slide 114 automatically return to normal position under the tension of a suitable spring, one end of which is connected to said device 116 and the other end of which is anchored to a stud projecting downwardly from the keeper 115. The normal position of this mechanism is clearly illustrated in Fig. 3 with the left end of the slide 114 projecting across the passageway in the chute 33 and abutting the inner surface of the wall member 16. The lower end of the spring-pressed bolt 117 is beveled so as to enable the same to be cammed upwardly out of the path of the rod 118 upon the return of the latter to normal position. The mechanism for discharging the twenty-five cent piece into the lower compartment B and the return of the proper change will now be described.

The coin stack or magazine 23 (see Fig. 5), which contains change for quarters, like the coin stacks 21, 22, 24, 25 and 26, is supported by a bracket 120 rigidly secured to the rear and one of the side walls, as shown in Figs. 2, 6 and 7. The magazine 23 is adjustably supported in the bracket 120 by means of the set screw 121. The lower end of the magazine is located at a certain distance from the partition wall 14. Adjustably supported upon the magazine 23 adjacent the lower end thereof, is a bracket 122 provided thereon with a spring pressed pawl 123 normally engaging the teeth on ratchet 124 which constitutes a part of the telescoping tube 125. The tele-

70

105

110

115

120

125

130

scoping tube 125 normally rests upon the division plate 14 under the tension of the springs 126. It is adapted to be raised to enable one, two, three or four five-cent coins to be discharged from the lower end of the stack depending upon the amount of change to be given, it being understood, of course, that if only five-cents change is to be given, then the tube is only raised a height equal to the thickness of one coin, etc.

Pivoted to the bracket 120 at the point 127 is a lever 128 provided upon one side of its pivot with a gear sector 129 and preferably a portion 130 encircling the tube, and provided at the other side of its pivot with an arm 131 adapted to be engaged by a plurality of spring pressed plungers 132, 133, 134 and 135. The intermediate portion 130 is provided with slots 136 adapted to be engaged by studs 137 fixed to the rods 138, which rods are operatively connected to the tubular member 125. The construction and arrangement is such, as will be clearly understood from a reference to Fig. 5, that when the plunger 132 is moved downwardly a predetermined distance, the telescoping tube 125 will be moved upwardly a distance equal to the thickness of one coin; that when the plunger 133 is moved downwardly the telescoping tube 125 will be raised for a distance equal to the thickness of two coins; that when the plunger 134 is moved downwardly the telescoping tube 125 will be raised for a distance equal to the thickness of three coins; and that 35 when the plunger 135 is moved downwardly, the telescoping tube 125 will be raised a distance equal to the thickness of four coins. Or, stated in another way, when four fares are to be taken from the twenty-five cent 40 piece deposited the plunger 132 is actuated; when three fares are to be taken the plunger 133 is actuated; when two fares are to be taken the plunger 134 is actuated; and when one fare is to be taken the plunger 135 is 45 actuated.

In the four respective cases just mentioned of raising the telescoping tube 125, it will be noted that in the first case, the pawl 123 will engage the lower end of the tooth 139; that 50 in the second case, it will engage with the lower side of the tooth 140; in the third case it will engage with the lower side of the tooth 141; and in the fourth case it will engage the lower side of the tooth 142. The ejector mechanism to be presently described is so constructed and arranged that in the four cases just mentioned one coin, two coins, three coins, or four coins are ejected from the lower 55 end of the pocket or magazine 23 depending upon the elevated position of the telescoping tube 125. Upon the lower side of the pawl 123 is a projection 143 adapted to be engaged by the error bar 144 mounted in brackets 145 and 146 (see Fig. 2) located at the opposite 60 sides of the machine and preferably sup-

ported by the division wall 14. Suitably connected to the bar 144 is a rod 147 slidably mounted in a bracket 148 and also in a bearing 149. Fixed upon the rod 147 is a rigid collar 150 and located between the bracket 148 and the collar 150 is a compression spring 151. On the rod, but located upon the opposite side of the bracket 148, is a stop 152 to limit the outward movement of the rod 147 under the force of the spring 151. The rod 147 is provided with a push button 153. The parts just described constitute error mechanism and by pushing inwardly upon the error key 153, the telescoping tube 125 can be restored to normal position. This is desirable 75 should the wrong plunger 132, 133, 134, or 135 be operated. Assuming that no error has been made, as will be the case in practically all operations of the plungers, the ejector mechanism is equipped with means operative upon 80 its return movement to normal position to engage the projection 143 and in like fashion restore the telescoping tube 125 to normal position in engagement with the division wall 14. This will be fully described below. 90

A fifth plunger 154 is employed to effect the simultaneous registration of five fares. This is accomplished in the following manner. Secured to the bracket 122 is a member 155 to which is pivotally connected an arm 156 carrying a suitable counter 157. This arm and counter are normally held in inoperative position by means of a spring 158. The outer end of the arm 156 is equipped with a latch member 159 so arranged that when the arm 156 is pushed downwardly by the plunger 154 the latch will engage with the member 155 and thereby maintain the arm 160 of the counter in the path of and to be engaged by the extension 161 of the ejector 108, in consequence of which the counter will be actuated, when so set as just described, upon the inward movement of the ejector. Upon the inward movement of the ejector, the member 161 cams the pivoted arm 162 out of its path but upon 105 its return movement, the engagement of the member 161 with the arm 162 will release the latch 159 thus enabling the counter to be restored to normally inoperative position under the tension of the spring 158. 110

Assuming that a twenty-five cent piece has been properly deposited in the lower portion of the coin passage 40, and the crosshead mechanism operated, the plunger 93 will engage with the twenty-five cent piece and move 115 the ejector 108 inwardly against the tension of spring 163. The ejector 108 is provided at an intermediate portion thereof with a plurality of longitudinal slots 164, 165, 166 and 167 (see Fig. 2) in which the pins 168, 169, 170 and 171 (see also Fig. 9) are adapted to reciprocate. These pins are fixed respectively in the ejecting plates 172, 173, 174 and 175. These ejecting plates are normally held 120 with the pins just referred to engaging the 125

rear end of said slots by means of the springs 176, 177, 178 and 179, one of the ends of which springs is attached to the said pins, and the other ends of which springs are attached to a member 180 projecting upwardly from the ejector 108. To this upright member is attached the spring 163 for maintaining the ejector in normal position. For the purpose of guiding the ejecting plates and for maintaining the same in cooperative relationship with the ejector, any suitable mechanism may be employed, but I prefer to provide a keeper 181 for that purpose.

Projecting rearwardly from the upright member 180 is an arm 182, the outer end of which is provided with a spring pressed member 183 freely movable in a rearward direction past the member 143 on the pawl 123. The member 183 is normally pressed into engagement with a stud 184 so that when the ejector 108, and therefore the arm 182, is returned to normal position, the member 183 engages with the projection 143 and disengages the pawl 123 from the rack member 124 thereby enabling the telescoping tube 125 to return to normal position. It will be noted that the construction and arrangement is such that when five fares are to be taken from the twenty-five cent piece deposited, the ejecting plates on the inward movement of the ejector 108 will all contact and be arrested in their movement by their engagement with the telescoping tube 125 and therefore no coin can be discharged from the lower end of the magazine 23. Remembering that when it is desired to receive four fares from the twenty-five cent piece deposited, that the telescoping tube 125 will be raised so as to enable the discharge of one coin from the bottom of the magazine 23 it will be apparent that upon the movement of the ejector 108 inwardly only the lower ejecting plate will be enabled to pass under the tube 125 and therefore only one coin discharged therefrom, the other ejecting plates being arrested by said tube 125. If the telescoping tube has been raised to take out three fares, only the two lower ejecting plates will pass under the lower end of the tube 125 and eject two coins from the magazine 23; and so on for the return of change after taking out two fares and one fare. During each operation, whether taking out one fare or any number of fares up to five fares from a twenty-five cent piece, the ejector 108 will be moved inwardly the same distance so as to enable the coin deposited to be discharged through the perforation 185 into the receptacle B.

The lower surface of the base plate is provided with two pawls 186 and 187 shown in Figure 9 having noses 188 and 189. The ejector 108 is provided on its opposite lower sides with two indentations 190 and 191 into which the noses of the pawls are adapted to engage. Upon the inward movement of the

ejector these indentations pass over the noses 188 and 189 but upon the return of the ejector the noses engage the same and maintain the ejector so as to enable the finger 93 to retreat slightly from the coin and thereby permit the latter to drop through the perforation 185 into the coin box B. The division wall 14 is provided with two perforations 192 and 193 through which the noses 188 and 189 project to engage the indentations 190 and 191, and to maintain the noses in engagement with the lower side of the ejector 108 I employ a pintle 194 common to the pawls 186 and 187 and the resilient means 195 connected thereto and to the division wall 14. The pawls 186 and 187 are provided with pivoted arms 196 and 197 normally resting upon the pintle 194 but movable freely in one direction therefrom to enable the studs 198 (only one shown) on the shaft 74 to pass the same in the operation of ejecting coins from the magazine. On the return movement, however, the studs 198 engage with the arms 196 and 197 thereby retracting, through pintle 194, the noses 188 and 189 from the indentations in the ejector 108 and enabling the latter to return to normal position under the tension of the spring 163. The pawls 186 and 187 and arms 196 and 197 are pivotally mounted on a common axis in the bearing members 199.

The sector 129 shown in Figures 2, 5 and 11 located upon the end of the pivoted arm 128 meshes with the gear 200 which is normally in suitable clutching engagement with a counter 201 mounted upon the shaft 202. Upon this same shaft is located a stop 203 and between the stop 203 and a collar 204 of said gear 200 is interposed a spring 205, the function of which is to maintain the gear 200 normally in clutching engagement with the counter. The depression of one of the keys 132, 133, 134 or 135 merely causes the sector to rotate the gear 200 idly. On the return movement of the sector, however, the gear 200 actuates the counter 201, to register the number of fares received. The details of the registering or counting mechanism are not illustrated. Reference has already been made to the fact that the wrong plunger may accidentally be operated thereby necessitating the operation of the error key 153 to enable the telescoping tube 125 to return to normal position. Unless some provision were made therefor, the return of the sector 129 to normal position would actuate the counter 201 and register the number of fares in accordance with the particular plunger depressed. To avoid this the rod 147 of the error key is provided with a cam surface 206 which engages with a pin 207 (see Figs. 5 and 10) on the declutching bar 208 impelling the latter to the left as viewed in Fig. 10. Engaging in a slot or notch 209 in the bar 208 is one end of a lever 210 pivoted at a

point 211 intermediate the declutching bar 208 and gear 200. The upper end of this lever is provided with a yoke 212, which straddles the collar 204. It will therefore be seen that when the declutching bar is moved to the left as viewed from Figs. 10 and 11, the gear 200 will be moved to the right to unclutch the same from the counter 201 thus enabling the sector 129 to return to normal position without actuating the counter. The declutching bar 208 is slidably mounted in the brackets 213 and 214 (see Figs. 2, 5, 10 and 11) secured to the interior casing of the machine. The counter shaft 202 is mounted in brackets 215 and 216 located upon the interior of the rear wall of the machine.

I have fully described above the manner in which the coins are inspected and operationally positioned in the bottom of the passageways 39, 40, 41 and 42. I have also fully described the manner in which change, if any, is to be returned when a quarter is deposited in the machine. And I have further described all of the mechanism of the machine in any way associated with the foregoing including the counting and error mechanisms. It remains, however, to describe the mechanism for returning, first, change for a dime, secondly, the change for a half-dollar, and thirdly, the change for a dollar. The same will be taken up for description in the order named.

Referring to Figs. 2, 6 and 7, which illustrate the mechanism for discharging the dime deposited into the lower compartment B and the return of the proper change the reference numeral 109, as before stated, designates the ejector employed in ejecting change from the lower end of the magazine 26. The ejector mechanism in this case is in all essential respects the same as that described above in connection with the return of change for a quarter. However, assuming that the fare is five cents it will be understood that at most it is only necessary in any event to return a nickel in change. Therefore only one ejecting plate 172a is required. When it is desired to return a nickel change for the ten-cent piece deposited the plunger 132a is actuated. This depresses the lever 217, and thus elevates the telescoping tube 125a a distance equal to the thickness of a nickel. At the same time the pawl 123a engages with the ratchet tooth 139a and holds the tube 125a in raised position until the ejecting plate is on its return movement to normal position, when the said pawl 123a will be engaged and released by the spring pressed member 183a. The associated mechanism not specifically referred to is the same as that described above in connection with the ejecting mechanism employed in conjunction with the twenty-five cent piece. When two fares are to be taken from the ten-cent piece the plunger 133a is actuated. This

depresses the lever 218 until the stud 219 engages the spring pressed latch member 220. Connecting the error bar 144 is a pivoted arm 221 adapted to release the latch 220 when the error mechanism is actuated. As the levers 217 and 218 return to normal position the racks thereon engage with pinions or gears on a suitable counter and register either one or two fares, as the case may be, and as will be understood. The member 180a is provided with an extension 222 so constructed and arranged that when the ejector is moved inwardly for a predetermined distance it will engage with and release the latch member 220 thereby enabling the lever 218 to return to normal position. The ejector 109 is controlled in its operation the same as ejector 108 previously described. In passing it may be stated that the racks upon the outer end of levers 217 and 218 are normally out of engagement with their gear or gears thus enabling one lever to actuate the counter independently of the other.

There are two magazines 21 and 22 containing the change for fifty-cent pieces deposited, one of which is supplied with quarters and the other of which is supplied with nickels. The specific construction illustrated enables the simultaneous reception of only five fares, so that the ejecting plate 223 is rigidly secured to the ejector 107 and always returns a quarter. The ejecting plates 172c, 173c, 174c and 175c (see Fig. 8) are constructed and operate the same as plates 172, 173, 174 and 175 previously described. In this case, however, only one pawl 186c (and associated mechanism) is illustrated.

The mechanism for returning the change for a dollar is the same in all essential respects as that employed for returning change for a fifty-cent piece deposited. However, the ejector and ejector plates are manually actuated by the rod 224 and push button 225. And the plate 226 ejects three quarters from the magazine 24 instead of one quarter. The rod 224 is directly connected to the ejector 227.

There has been described herein and diagrammatically illustrated in the drawings, suitable counter mechanism for registering or checking the number of fares received by the operator. The invention is admirably adapted for use with a turnstile and when so used the machine can be materially simplified by omitting the counter mechanism illustrated and providing a suitable counter on the turnstile.

In Figs. 13 and 14 I have illustrated a modified form of that portion of my invention having to do with the registration of fares. In the preceding description, the arrangement of the plunger registering mechanism is such that the amount of change returned is counted, whereas with the construction illustrated in Figs. 13 and 14 the

actual number of fares is registered. Briefly stated, this comprises two plunger actuated levers 228 and 229, the former of which is pivotally connected at 230 to the bracket 120 and to the rods 138 as before and the latter of which is pivoted at 231 to the casing of the machine and is equipped at its other end with a sector 232 held in normal position by means of the spring 233. It will therefore be noted that a downward movement of any particular plunger will impart through the lever mechanism illustrated and described, a downward movement to the sector 232. It will be understood that the clutch mechanism in this case is so constructed that the gear 234 will move freely on the downward movement of the sector. At a predetermined point in its downward travel, the lever 229 is locked against returning by the mechanism previously described. The counters are actuated on the return of lever 229 and the sector 232 to normal position, as will be understood.

From the foregoing it will be manifest that I have devised a multiple fare change machine which is simple in construction, easy to manipulate, and not liable to get out of order. The construction of my invention illustrated and described herein is merely the preferred embodiment thereof, and it is to be expressly understood that I do not limit myself thereto, as many changes may be made in points of detail and other embodiments devised and resorted to without departing from the true spirit and scope of my invention. In this connection reference is hereby made to my copending application, Serial No. 354,491, filed April 12, 1929, wherein I have claimed certain features of my invention shown and described herein; in other words, the patentable subject matter common to this application and my said copending application is claimed in the latter.

What I claim is:

1. A change making machine comprising a plurality of change pockets therein, means for receiving deposited coins, ejectors corresponding to the denomination of coin deposited and located in operative relationship to said pockets, means common to said ejectors and rendered operative by and including the deposited coins of different denominations for actuating that ejector corresponding to the denomination of coin deposited, and means for determining whether one or more than one coin will be ejected from each pocket by said ejecting means.

2. A change making machine comprising a plurality of change pockets, a chute for receiving deposited coins, mechanism for each of said pockets for ejecting change therefrom, mechanism rendered operative by and including the deposited coins for actuating said ejecting mechanism, means for normally arresting the coins as they pass

into the coin chute to prevent jamming, and means operated by said actuating mechanism for rendering the coin arresting means inoperative.

3. A change making machine comprising a plurality of change pockets, and means for ejecting change from said pockets, in combination with means rendered operative by and including the deposited coin for determining from which carrier the change is to be ejected, and means for determining whether one or more than one coin will be ejected from each of said pockets by said ejecting means. 70

4. A change making machine comprising a plurality of change pockets, an ejector mechanism for each of said pockets, means common to all of said ejectors for actuating any one of the same, said means being rendered operative by the deposit of coins for which change is to be made, and means for determining whether one or more than one coin will be ejected from each pocket by said ejecting means. 80

5. A change making machine comprising means for depositing coins of different denominations, a plurality of change carriers, ejector mechanism for each of said carriers, normally inoperative mechanism common to all of said ejectors for actuating the same, 90 said second mentioned mechanism being provided with means cooperating with and including the coin deposited to render the same operative to actuate one of said ejector mechanisms, and means for adjusting one of said ejector mechanisms to discharge one or more change coins. 95

6. A change making machine comprising a plurality of change pockets for receiving change for coins of different denominations, means for receiving deposited coins of different denominations, means rendered operative by and including the deposited coin for ejecting change from one of the pockets, and means for determining whether one or more than one coin will be ejected from said pocket by said ejecting means. 100 110

7. A change making machine comprising a plurality of change pockets therein, means for receiving the deposited coins, ejecting mechanism located in operative relationship to the change in one of said pockets, means rendered operative by and including the deposited coin for actuating said ejecting mechanism, and means for determining whether one or more than one coin will be ejected from said pocket by said ejecting means. 115

8. A change making machine comprising a plurality of change pockets therein, means for receiving deposited coins, ejecting mechanism located in operative relationship to one of the pockets to discharge change therefrom, means rendered operative by and including the deposited coin as an operative part thereof for actuating said ejecting mech- 120 125

anism, means rendering said ejecting means normally inoperative to return any change, and selecting means for rendering said ejecting mechanism operative to return a predetermined amount of change.

9. A change making machine comprising a plurality of change pockets therein, for receiving change for coins of different denominations, means for receiving deposited coins, 10 an ejector for each pocket of different denomination located in operative relationship thereto, means common to said pockets and rendered operative by and including the deposited coins of different denominations as 15 an operative part thereof for actuating that ejector corresponding to the denomination of coin deposited, means for rendering said ejecting means inoperative to return any change, and means for rendering said ejecting mechanism operative to return a predetermined amount of change.

10. A change making machine comprising a change carrier, a chute for receiving deposited coins, mechanism cooperating with 25 said carrier for ejecting change therefrom, mechanism rendered operative by the deposit of coins for actuating said ejecting mechanism, means for normally arresting the coin as it passes into the coin chute to enable it 30 to be inspected, means actuated by said mechanism for rendering the coin arresting means inoperative, and means for rendering said ejecting mechanism operative to return a predetermined amount of change.

35 11. A change making machine for registering multiple fares, comprising a plurality of change pockets, a chute common to said pockets for receiving the coins deposited for change and for locating the coins therein of 40 different denominations in certain positions, means common to the pockets and rendered operative by and including the particular coin deposited as an operative part thereof for ejecting change from one of said pockets, 45 said means comprising mechanism for ejecting one or a plurality of change coins from said pocket.

50 12. A change making machine comprising, a plurality of change pockets, an ejector crosshead common to all the pockets, an ejector for each pocket adjacent the crosshead, said ejector being operated by the crosshead when a deposited coin is interposed between the crosshead and ejector, and means for 55 raising the pockets to enable the ejector to pass underneath the pocket and eject a change coin therefrom.

60 13. A change making machine comprising a plurality of change pockets, an ejector crosshead common to all the pockets, an ejector for each pocket adjacent the crosshead, said ejectors being operated by the crosshead when a deposited coin is interposed between the cross head and the ejector, a plurality of 65 ejector plates resiliently connected to the

ejector for at least one pocket, means for raising at least one pocket and to vary the clearance and the number of ejector plates capable of passing underneath the pocket and thereby varying the number of change coins ejected by the ejector from one pocket.

70 14. A change making machine comprising a plurality of vertically movable change pockets, an ejector crosshead common to all the pockets, a plurality of ejector plates for each pocket adjacent the crosshead, said ejectors being operated by the crosshead when a deposited coin is interposed between the crosshead and the ejector, means to raise the pockets a distance equal to one or more ejector plates, at least one indentation in an ejector plate, an ejector pawl adapted to enter the indentation when the ejector plate is operated thereby holding it in operated position and freeing the coin upon withdrawal of the crosshead, and means to release the ejector pawl.

75 15. A change making machine comprising a plurality of change pockets, an ejector crosshead common to all the pockets, an ejector for each pocket adjacent the crosshead, said ejectors being operated by the crosshead when a deposited coin is interposed between the cross head and the ejector, a plurality of 80 ejector plates resiliently connected to the ejector for at least one pocket, means for raising at least one pocket to vary the clearance and the number of ejector plates capable of 85 passing underneath the pocket and thereby varying the number of change coins ejected by the ejector from one pocket, at least one indentation in said ejector, an ejector pawl adapted to enter the indentation when the ejector is operated thereby holding it in operated position and freeing the coin upon withdrawal of the crosshead, and means to release the ejector pawl.

90 16. A change making machine comprising a plurality of change pockets, an ejector crosshead common to all the pockets, an ejector for each pocket adjacent the crosshead, said ejectors being operated by the crosshead when a deposited coin is interposed between the crosshead and the ejector, a plurality of 95 ratchet teeth upon at least one of the said change pockets, a pawl adapted to engage said ratchet teeth to raise the pocket to vary the clearance and the number of ejector plates capable of passing underneath the pocket and thereby varying the number of change coins 100 ejected by the ejector from one pocket, and means to operate said pawl.

105 17. A change making machine comprising a plurality of change pockets, an ejector crosshead common to all the pockets, an ejector for each pocket adjacent the crosshead, said ejectors being operated by the crosshead when a deposited coin is interposed between the cross head and the ejector, a plurality of 110 ratchet teeth upon at least one of the change 115 pockets, a pawl adapted to engage said ratchet teeth to raise the pocket to vary the clearance and the number of ejector plates capable of passing underneath the pocket and thereby varying the number of change coins 120 ejected by the ejector from one pocket, and means to operate said pawl.

5 pockets, a ratchet pawl engaging said ratchet teeth to raise the pocket and vary the clearance and the number of ejector plates capable of passing underneath the pocket and thereby varying the number of change coins ejected by the ejector from one pocket, a pivoted lever connected to said ratchet pawl, and a plurality of means adapted to engage said pivoted lever at different distances from the pivot thereby varying the distance through 10 which the pawl and change pocket is raised.

15 18. A change making machine comprising a plurality of change pockets, an ejector crosshead common to all the pockets, an ejector for each pocket adjacent the crosshead, said ejectors being operated by the crosshead when a deposited coin is interposed between the cross head and the ejector, a plurality of ratchet teeth upon at least one of 20 the change pockets, a ratchet pawl engaging said ratchet teeth to raise the pocket and vary the clearance and the number of ejector plates capable of passing underneath the pocket and thereby varying the number of change coins 25 ejected by the ejector from one pocket, a pivoted lever connected to said ratchet pawl, a plurality of means adapted to engage said pivoted lever at different distances from the pivot thereby varying the distance through 30 which the pawl and change pocket is raised, and means to release the ratchet pawl thereby returning the change pocket to its original position.

35 19. A change making machine comprising a plurality of change pockets, an ejector crosshead common to all the pockets, an ejector for each pocket adjacent the crosshead, said ejectors being operated by the crosshead when a deposited coin is interposed between 40 the crosshead and the ejector, a telescoping tube slidable on one of said change pockets, a plurality of ratchet teeth upon said telescoping tube, a ratchet pawl engaging said ratchet teeth to raise the telescoping tube and vary the clearance and the number of 45 ejector plates capable of passing underneath the pocket, and thereby varying the number of change coins ejected by the ejector from one pocket, a pivoted lever connected to said ratchet pawl, a plurality of means adapted to engage said pivoted lever at different distances from the pivot thereby varying the distance through which the pawl and change 50 pocket is raised, and means to release the ratchet pawl thereby returning the telescoping tube to its original position.

55 20. A change making machine comprising a plurality of change pockets, an ejector crosshead common to all the pockets, an ejector for each pocket adjacent the crosshead, said ejectors being operated by the crosshead when a deposited coin is interposed between the crosshead and the ejector, a telescoping tube slidable on one of said 60 change pockets, a plurality of ratchet teeth

upon said telescoping tube, a ratchet pawl engaging said ratchet teeth to raise the telescoping tube and vary the clearance and the number of ejector plates capable of passing underneath the pocket and thereby varying the number of change coins ejected by the ejector from one pocket, a pivoted lever connected to said ratchet pawl, a plurality of means adapted to engage said pivoted lever at different distances from the pivot thereby varying the distance through which the pawl and change pocket is raised, and said ejector being adapted to release said ratchet pawl upon its return movement thereby returning the telescoping tube to its original position. 70

75 21. A change making machine comprising a plurality of change pockets, an ejector crosshead common to all the pockets, an ejector for each pocket adjacent the crosshead, said ejectors being operated by the crosshead when a deposited coin is interposed between the crosshead and the ejector, a telescoping tube slidable on one of said change pockets, a plurality of ratchet teeth upon said telescoping tube, a ratchet pawl engaging said ratchet teeth to raise the telescoping tube and vary the clearance and the number of ejector plates capable of passing underneath the pocket and thereby varying the number of change coins ejected by the ejector from one pocket, a pivoted lever connected to said ratchet pawl, a plurality of means adapted to engage said pivoted lever at different distances from the pivot thereby varying the distance through which the pawl and change 80 pocket is raised, said ejector being adapted to release said ratchet pawl upon its return movement thereby returning the telescoping tube to its original position. 85

90 22. A change making machine comprising, a plurality of change pockets, an ejector crosshead common to all the pockets, an ejector for each pocket adjacent the crosshead, said ejectors being operated by the crosshead when a deposited coin is interposed between the crosshead and the ejector, a plurality of ratchet teeth upon at least one of 95 the change pockets, a ratchet pawl engaging said ratchet teeth to raise the pocket and vary the clearance and the number of ejector plates capable of passing underneath the pocket and thereby varying the number of change coins ejected by the ejector from one pocket, a pivoted lever connected to said ratchet pawl, a plurality of means adapted to engage said pivoted lever at different distances from the pivot thereby varying the distance through which the pawl and change 100 pocket is raised, said ejector being adapted to release said ratchet pawl upon its return movement thereby returning the telescoping tube to its original position, and an error key adapted to release said ratchet pawl in case an error in the machine setting has been made. 105

110 22. A change making machine comprising, a plurality of change pockets, an ejector crosshead common to all the pockets, an ejector for each pocket adjacent the crosshead, said ejectors being operated by the crosshead when a deposited coin is interposed between the crosshead and the ejector, a plurality of ratchet teeth upon at least one of 115 the change pockets, a ratchet pawl engaging said ratchet teeth to raise the pocket and vary the clearance and the number of ejector plates capable of passing underneath the pocket and thereby varying the number of change coins ejected by the ejector from one pocket, a pivoted lever connected to said ratchet pawl, a plurality of means adapted to engage said pivoted lever at different distances from the pivot thereby varying the distance through which the pawl and change 120 pocket is raised, a segmental gear secured to the lever, a gear adapted to mesh with and be rotated by said segmental gear upon a predetermined movement of the segmental 125 gear. 130

gear, a shaft upon which said gear is rotatable and movable axially, a ratchet upon said gear, a registering device, a ratchet upon said registering device engaging the gear ratchet 5 for rotation in one direction, a spring resiliently pressing said gear axially thereby engaging the ratchets which causes rotation of the registering device in one direction.

23. A change making machine comprising 19 at least one vertically movable change pocket, an ejector member adjacent to the bottom of each pocket, a plurality of ejector plates resiliently connected to said ejector members and disposed upon each other, a movable cross-head adjacent to said ejector members and imparting movement to the ejector member upon insertion of a deposited coin therebetween, and means to raise said change pocket in accordance with the number of coins to be 20 ejected therefrom.

24. A change making machine comprising at least one vertically movable change pocket, a plurality of movable ejector plates disposed upon each other adjacent the bottom of the 25 change pocket, a crosshead common to said pockets and adjacent to the ejector plates for moving the ejector plates upon insertion of a deposited coin between the crosshead and the ejector plates, a resilient connection between 30 the crosshead and the ejector plates, and means to raise the change pockets to eject one or more coins therefrom.

25. A change making machine comprising a plurality of change pockets therein, means 35 for receiving deposited coins, ejectors corresponding to the denomination of coin deposited and located in operative relationship to said pockets, means common to said ejectors and rendered operative by and including the 40 deposited coins of different denominations for actuating that ejector corresponding to the denomination of coin deposited, and means for determining whether one or more than one coin will be ejected from each pocket 45 by said ejector.

26. A change making machine comprising a plurality of change pockets, and means for 50 ejecting change from said pockets, in combination with means rendered operative by and including the deposited coin for determining from which pocket the change is to be ejected, and means for determining whether one or more than one coin will be ejected from 55 each of said pockets by said ejecting means.

27. A change making machine comprising a plurality of change pockets, ejector mechanism for each of said pockets, means common to all of said ejectors for actuating any 60 one of the same, said means being rendered operative by and including the deposited coins for which change is to be made, and means for determining whether one or more than one coin will be ejected from each pocket 65 by said ejector mechanism.

28. A change making machine comprising means for depositing coins of different denominations, a plurality of change carriers, ejector mechanism for each of said carriers, normally inoperative mechanism common to all of said ejectors for actuating the same, said second mentioned mechanism being provided with means cooperating with and including the coin deposited to render the same operative to actuate one of said ejector mechanisms, and means for selectively adjusting one of said ejector mechanisms to discharge one or more change coins. 70

29. A change making machine comprising a plurality of change pockets, a chute for receiving the coin deposited, means rendered operative by and including the deposited coin for simultaneously ejecting change from a plurality of said pockets, and means for determining whether one or more than one coin will be ejected from said pockets by said ejecting means. 80

30. A change making machine comprising a plurality of change pockets for receiving change for coins of different denominations, means for receiving deposited coins of different denominations, means rendered operative by and including the deposited coin for ejecting change from one of the pockets and means for determining whether one or more than one coin will be ejected from said pocket by said ejecting means. 90

31. A change making machine comprising a plurality of change pockets therein, means for receiving the deposited coins, ejecting mechanism located in operative relationship to the change in one of said pockets, means rendered operative by and including the deposited coin for actuating said ejecting mechanism, and means for determining whether one or more than one coin will be ejected from said pocket by said ejecting mechanism. 100

32. A change making machine comprising a plurality of change pockets, a chute for receiving a deposited coin, common means rendered operative by and including the deposited coin for simultaneously ejecting change from a pair of said pockets, and means for determining whether one or more than one coin will be ejected from one of the pockets 110 of said pair of pockets by said ejecting means. 115

33. A change making machine comprising a plurality of change pockets, a chute for receiving a deposited coin, an ejector common to said pockets, means rendered operative by and including the deposited coin for actuating said ejector, and means for determining whether one or more than one coin will be ejected from said pockets by said ejector. 120

34. A change making machine comprising a plurality of change pockets, a chute for receiving a deposited coin, ejectors for certain of said pockets, an ejector common to a group of other pockets of said plurality of pockets, means common to said ejectors and 125 130

rendered operative by and including the deposited coin for actuating the same to eject change from said pockets, and means for determining whether one or more than one coin will be ejected from said group of pockets by said ejector.

35. A fare collecting and change making machine comprising a plurality of change pockets, means for receiving deposited coins, ejectors corresponding to the denominations of the coins deposited, means for registering the fares collected from the coin deposited, means for simultaneously controlling the number of change coins to be ejected from one of said pockets and the number of fares to be recorded as collected, in combination with means common to said ejectors and rendered operative by and including the deposited coin for simultaneously actuating that ejector corresponding to the denomination of the coin deposited to eject change therefor and actuating said fare registering means.

36. A change making machine comprising change return mechanism, a chute for receiving the coin, a passageway for conducting the coin from said chute into the machine, and a second passageway for conducting said coin to the exterior of the machine, in combination with means for selectively discharging said coin from said chute into either of said passageways, normally operative means for arresting the coin in said chute, and mechanism including a deposited coin for actuating said change return mechanism, said actuating mechanism comprising means for rendering said arresting means temporarily inoperative.

37. A change making machine comprising a change return mechanism, a coin chute, means for normally closing the coin chute, a passageway for conducting the coin from said chute into the machine, a second passageway for conducting the coin to the exterior of the machine, in combination with means for discharging said coin selectively into either of said passageways, said mechanism comprising means including a deposited coin for rendering said closing means temporarily inoperative and for actuating said change return mechanism.

38. In a change making machine, a change return mechanism, and means for receiving a coin into operative position in the machine comprising a chute, and means for arresting a coin in said chute, in combination with mechanism including a deposited coin for actuating said change return mechanism, said actuating mechanism including means for operating said arresting means to release the coin, and automatic means for returning said arresting means to normal position to prevent the deposit of a second coin into said receiving means.

39. A change making machine comprising change return mechanism, a chute for receiv-

ing a deposited coin, means for arresting the coin in said chute, a passageway for conducting said coin from said chute into the machine, a passageway adapted to conduct said coin to the exterior of the machine, in combination with mechanism for selectively discharging said coin into either of said passageways, said second mentioned mechanism comprising means for actuating the coin arresting means, and also comprising means including a deposited coin adapted to actuate said change return mechanism.

40. In a change making machine, a change carrier, a chute for receiving deposited coins, mechanism cooperating with said carrier for ejecting change therefrom, and mechanism rendered operative by a deposited coin for actuating said ejecting mechanism, in combination with means for discharging the coin from said chute into operative position in the machine comprising mechanism for arresting the coin in said chute, means operated by said actuating mechanism for rendering the coin arresting means temporarily inoperative, and means for automatically restoring the arresting means to normal position to prevent the depositing of a second coin.

41. In a change making machine, a change carrier, a chute for receiving deposited coins, mechanism cooperating with said carrier for ejecting change therefrom, and mechanism rendered operative by the deposited coin in operative position in the machine for actuating said ejecting mechanism, in combination with means for discharging a coin from said chute into operative position in the machine or for ejecting the same comprising means for arresting the coin in said chute, selector mechanism, means operated by said actuating mechanism for rendering the coin arresting means temporarily inoperative to enable a coin to be discharged into said selector mechanism, means for actuating said selector mechanism to discharge the coin into operative position in the machine or to eject the same therefrom, and means for automatically restoring the arresting means to normal position to prevent the depositing of a second coin during the operation of the machine.

42. A change making machine comprising change return mechanism, a chute for holding a coin, means for arresting a coin in said chute, a passageway for conducting the coin from said chute to its operative position in the machine, a second passageway for conducting the coin to the exterior of the machine, and mechanism for actuating said change return mechanism including a deposited coin, in combination with mechanism for discharging said coin into either of said passageways comprising selector mechanism adapted to receive the coin from the arresting means, means operated by said actuating mechanism for rendering the coin arresting means temporarily inopera-

tive, and means for automatically restoring the arresting means to normal position to prevent the discharge to said selector mechanism of a second coin.

- 5 43. A change making machine comprising change return mechanism, a chute for receiving a coin, means for arresting the coin in said chute, a passageway for conducting the coin from said chute to its operative position
10 in the machine, and a passageway for conducting the coin from said chute to the exterior of the machine, in combination with mechanism for actuating the coin arresting means and to discharge the coin from said
15 chute selectively into either of said passageways, said last mentioned mechanism comprising means for actuating the coin arresting means and thru the intermediary of the coin deposited for thereafter actuating the
20 change return mechanism.

44. A change making machine comprising a change return mechanism, and means for receiving a deposited coin into operative position in the machine, said means comprising
25 an automatically operated normally operative device for preventing the deposit of a second coin therein, in combination with mechanism including a deposited coin for actuating said change return mechanism,
30 said actuating mechanism comprising means for rendering said device momentarily inoperative so as to enable another coin to be deposited into operative position in said receiving means.

- 35 45. A change making machine comprising a plurality of change pockets, a chute for receiving the coin deposited, means rendered operative by and including the deposited coin for simultaneously ejecting change from a plurality of said pockets, and means for determining whether one or more than one coin will be ejected from said pockets by said ejecting means.

45 In testimony whereof, I have hereunto set my hand and affixed my seal this 12th day of January, 1923.

CHARLES E. CHALMERS.

CERTIFICATE OF CORRECTION.

Patent No. 1,801,794.

Granted April 21, 1931, to

CHARLES E. CHALMERS.

It is hereby certified that error appears in the printed specification of the above numbered patent requiring correction as follows: Page 2, line 36, strike out the word "or"; page 9, line 85, claim 4, for "the deposit of" read and including the deposited; page 10, line 67, claim 13, strike out the word "and" and insert the same after "pocket" in line 66, same claim; page 13, lines 123 and 124, claim 42, strike out the words "including a deposited coin" and insert the same after the word "mechanism" in line 122, same claim; and that the said Letters Patent should be read with these corrections therein that the same may conform to the record of the case in the Patent Office.

Signed and sealed this 1st day of September, A. D. 1931.

(Seal)

M. J. Moore,
Acting Commissioner of Patents.
